UNITED STATES PATENT OFFICE

RICHARD MERCER, OF HARROW, ENGLAND. ASSIGNOR TO ASSOCIATED TELEPHONE & TELEGRAPH COMPANY, OF KANSAS CITY, MISSOURI, A COMPANY OF DELAWARE

TELEPHONE SYSTEM

Application filed February 26, 1927, Serial No. 171,118, and in Great Britain March 26, 1926.

The present invention relates to improvements in or relating to telephone systems and while it more particularly applies to the systems employing register translators, it should be understood that it is not exclusively limited thereto.

It has been proposed in large networks to arrange for the directory number which is dialled by a calling subscriber in calling another, to consist of three letters, namely the first three letters of the name of the exchange to which the wanted party's line is connected and four figures. For this purpose the dial switch is provided with two or three letters in the various finger holds, as well as a figure. Normally there would be approximately 1000 combinations in which these three digits could be arranged but obviously there are certain limitations in practice, one of which is that it is undesirable to have any letters in the finger hold 1, unless the letter I, and only one O in the finger hold 0, and further that the possible number of combinations capable of forming part of exchange names is very much less than the number of combinations which may be obtained. Actually however there is no difficulty in getting from up to 100 to 200 exchange names which will meet these conditions in a given network. Where there are considerably less exchanges in a network than 100 it is not essential to use three digits of the exchange name, and accordingly it has been proposed to use two. This enables the register translator apparatus to be considerably simplified. For instance, in the patent to Richardson et al., 1,702,392, Feb. 19, 1929, the first digit of an exchange name is caused to operate what is known as an 'A' digit selector. This switch responds to the first digit and then selects an idle register translator where the next two digits are stored, the whole three digits are then translated in a suitable manner. In a two digit area it is possible to eliminate the first set of switches shown as 'A' digit selectors and thereby effect a considerable economy.

One of the great advantages of a system employing three digits to correspond to the exchange required is that these three digits

usually lend themselves to a simple pronunciation which further assists the memory in addition to the factor that these are the first three letters of the exchange name; secondly, persons who are likely to use the telephone both in two digit and three digit areas are quite likely to make a mistake and dial an extra digit, or a digit short, when in the wrong area. This would result either in connecting to a wrong number with natural annoyance to the party disturbed, or not connecting to any number at all. Thirdly, a telephone network may develop to such a size that the addition of further exchanges will necessitate the conversion from a two digit to a three digit network. This would of course necessitate the complete change of the directories and the retraining of all the subscribers into making use of the third letter of the exchange name.

The object of the present invention is to avoid all these disadvantages, while retaining the economical advantages of a two digit register translator for a greater number of exchanges than is now possible, and according to the principal feature of the invention, arrangements are provided in a two digit area for arranging that the subscriber must dial three digits and arranging for one of the digits either to be suppressed or to be routed away from the normal receiving apparatus. Owing to the fact that there are only five vowels, and in a large majority of exchange names the second digit tends to be a vowel, it will happen that in areas where two digits are dialled by a calling subscriber, the limitation of the number of exchange names available will be less if the first and third digit is used to distinguish the exchange name, than if the second was used in conjunction with either of the others. For instance it has been found in the London area, taking 101 exchange names of which the first three letters when dialled by the dial adopted for the London area will give 101 different signals, that if only the first two letters are used the 101 exchange names will give only 43 different signals, whereas if the first and third letters are used 54 different signals are given. Consequently it may become necessary to convert an area and install the

extra apparatus required at a very much earlier date if the second digit is made use of, than if the first and third digits were made effective on the registering apparatus and the 5 second digit suppressed.

Accordingly a second feature of the present invention is to arrange for the suppression of the second digit of the exchange name dialled by a subscriber. It should be understood 10 that it will be necessary to modify in any network not only the arrangements which respond to the impulses dialled by a calling subscriber, but also the operator's impulse senders where these are operated on a similar 15 code to the subscriber as regard the exchange name. In the accompanying drawings arrangements are shown which relate to arrangements which respond to impulses dialled by a calling subscriber, but it will be 20 clear to those versed in the art that a modification could be made to an operator's control impulse sending arrangement, such for instance, as is described in the patent to Garrings, 1,705,832, March 19, 1929, by a somewhat 25 similar arrangement, modified only in that a key pressing operation is rendered non-effective instead of a series of impulses.

The accompanying drawings, Figs. 1 and 30 2, illustrate two alternative arrangements of carrying the invention into effect. These drawings show only that part of the apparatus which requires altering from standard constructions. As an example of such constructions, the patent to Bellamy et al., 35 1,683,857, Sept. 11, 1928, is referred to, and it will be found that Fig. 1 of the present drawings substantially corresponds to Fig. 2 of the drawings shown in the above-mentioned specification. Fig. 2 is similar and corresponds 40 to the left-hand side of Fig. 1.

In the first place reference will be had to Fig. 1 and the operation of the switch S will be briefly described, all other particulars being obtainable by reference to the said patent 45 to Bellamy et al., although this is not necessary for an understanding of the present invention as arrangements such as the switch S are common to all systems of this type.

To describe the operation of the invention 50 with relation to this figure, it will be sufficient to refer to the operation of the system but this need only be done in a general way. For this purpose when the subscriber operates his dial for the first letter, impulses are sent over the lead 75, which pass over the slow acting relay 102, wiper 107, the second contact, terminal 5 of the terminal block TB to terminal 1 and thence over the lead 121 to the vertical magnet of the registering switch.

55 It will be assumed in this case only a two digit system is being described, as is shown in the above patent to Bellamy et al. Relay 102 energizes in this circuit and thereby energizes relay 101. At the end of a series of 60 impulses, relay 102 de-energizes and com-

pletes at contacts 114 a circuit for the stepping magnet 103 of the switch S. The wipers 106 and 107 thereupon advance one step so that the next series of impulses is routed over lead 75, relay 102, wiper 107, contact 6, 70 contact 3 to lead 122 and thence to the second or rotary magnet of the register switch so that the second digit is recorded. At the end of the series of impulses the magnet 103 steps as before to connect earth to lead 114' 75 to initiate the impulse sending and permits a subsequent series of impulses to be sent over lead 131, 132, 133 and 134 successively. When it is desired to restore the switch S to normal, earth is connected to the lead 113, whereupon the release magnet 104 energizes and restores the switch to normal. In the present case the switch S has been provided with one additional contact position, and with adjustable means AM to prevent the switch restoring to the additional contact so that as shown, this contact is entirely out of action. Consequently as has been described, the modification so far makes no difference whatever to the operation as described in connection 90 with the Bellamy et al. patent. Assume however that it is desired to modify the director so as to receive three letters and to suppress the second, then the adjusting means AM 95 for the wipers are modified so that the normal position is such that the normal or additional contact is connected to by wipers 106 and 107 when in the normal position, and in consequence of which the first series of impulses is received, that is from over lead 75, relay 102, wiper 107, contact 4, contact 1, terminal block TB to lead 121 and thence to the rotary magnet. The second series of impulses passes over lead 75, 100 relay 102, wiper 107, contact 5, contact 2, resistance 7 back to battery. This series of impulses therefore is routed away from and has no effect upon the normal registering apparatus. The third series of impulses then passes over the patch 75, relay 102, wiper 107, terminal 6, terminal 3, lead 122 to the second or rotary magnet of the register. Consequently the first and third digits operate the 105 registering mechanism. The arrangement for restoring to normal is the same as before, 110 but the wiper 106 does not become effective to control the transmission of impulses until the third digit has been sent. This is necessary as the transmission of impulses should not commence and does not commence until after 115 the three letters of the exchange name have been received.

120 It will thus be appreciated that by a simple mechanical modification the switch S can respond to either two or three digits and effect appropriate control accordingly. All that is necessary is to modify the connections at the terminal end and to modify the normal position of the wipers both of which can be done very rapidly. 125 130

In Fig. 2 the switch S2 is similar to the switch S as regards its operating function but differs in that while the switch S is a switch which moves in one direction against spring pressure and is restored to normal by the operation of the release magnet, and the restoring spring, the switch S2 moves continuously forward so that one arm of a plurality with which each wiper is provided, is always engaging with a contact. In place of off-normal springs, and additional contact bank and wiper 8 is provided. The wipers are given the same reference letters as the wipers 106 and 107 because their function is identical with that described in Fig. 1. The terminal block however is slightly increased in size as all the modifications necessary can be effected therewith. Where the register has to respond to two digits and to record two digits, the contacts 9 and 12 are connected together as well as contacts 11 and 14, consequently when earth is placed on conductor 113 the wiper 8 will move to rest on the second contact, which is insulated, contact 13 not being connected up. If however, it is desired to receive three impulses and the register mechanism has only to respond to two, namely the first and third, then contacts 10 and 13 and 11 and 14 are connected up and the wiper 8 will then move into the position shown in the drawings if earth is connected to lead 113, and the wiper is resting in any position other than the position shown. It does not appear to be necessary to describe the other part of the apparatus which is, as previously stated, identical with that shown in Fig. 1.

It is of course clear that if for any reason it may be desirable to suppress the first letter or the third letter in place of the second, this could be readily effected, although it is believed that the arrangement shown would probably prove in practice to be that most desirable, that is the arrangement by which three impulse series are received and the first and third are utilized until the second is required.

What I claim as new and desire to secure by Letters Patent is:—

1. A telephone system in which the initial letters of names of exchanges in a network are transmitted to receiving apparatus in the same manner as the numbers of wanted subscribers, characterized in that the receiving apparatus is provided with terminal arrangements in a readily accessible position with connections thereto so arranged that by modifying the inter-connections between the terminals the receiving arrangements can respond to either two or three initial letters of names of the exchanges in accordance with the number of exchanges in the network.

2. A register sender for use in telephone systems adapted to receive a plurality of series of impulses corresponding to the letters

of an exchange name, to suppress one or more of said letters, and to record the remaining letter or letters.

3. A register sender adapted to respond to either two or three series of impulses and provided with a terminal block by which a particular two of the three series of the impulses may be made effective or two series may be made effective when three letters are received.

4. In a telephone system in which initial letters of names of exchanges are transmitted in the same manner as the numbers of desired subscribers and in which the transmitted letters and numbers are received by the registering apparatus of switch-controlling register senders, letter-registering means included in the registering portion of the register senders for registering one less letter than is received, and means included in the registering apparatus for absorbing, without registering, the other received letter.

5. In a multi-office telephone system in which the complete number of a subscriber comprises the first three letters of an office name followed by the digits necessary to distinguish the line of that subscriber from the other lines terminating in the same office, and in which registering and retransmitting apparatus is provided to respond to the transmission of a subscriber's number and to control the necessary switches to complete the connection, registering means and non-registering absorbing means included in the registering apparatus of the register senders whereby the first and third letters of the office designation are registered and the second letter is absorbed instead.

6. In a registering device for use in a telephone system in which the complete number of a subscriber includes the first three letters of the name of the office in which his line terminates, an input-control switch arranged to shift the registering circuit after each digit, register devices connected to each position of said input-control switch except the second, and circuit arrangements for advancing said impulse control switch through its second position responsive to the receipt of the second letter of the office name.

7. In a registering device including a two-motion register for use in a telephone system wherein the first three characters in a number are the first three letters in an office name, means for operating said register in its first motion to record the first character of a number, for receiving the second character of the number, and for operating said registering device in its second motion to register the third character in the number.

8. In a registering device having associated therewith a multi-position sequence switch, means responsive to the receipt of trains of impulses for suitably advancing said sequence switch so that it is in its first position while

- the first train is being received, is in its second position while the second train is being received, and is in its third position while the third train is being received, registering apparatus responsive to the first and third trains of impulses and non-responsive to the second train of impulses, whereby the second train of impulses is absorbed and is not registered.
9. In a telephone system wherein registering and retransmitting apparatus is provided to receive and register characters in telephone designations and to control automatic switching apparatus to set up connections, means included in the registering portion of the registering and retransmitting apparatus for registering one less character than is received in a set of characters, and means associated with the said registering apparatus for absorbing, without registering, the other received character.
10. In a device arranged to register a plurality of groups of electrical impulses, a separate receiving conductor for each group of impulses, a distributing device having a normal position and having arrangements associated therewith for advancing it between groups of impulses to direct the groups of impulses to the said receiving conductors, and means for mechanically altering said distributing switch so that one of the off-normal positions thereof becomes its normal position.
11. A progressively-movable, impulse-operated, step-by-step switch arranged to be operated from a normal position into a particular off-normal position corresponding to the number of received impulses, means for retracting said switch to its normal position, and means for adjusting said switch so that the normal position thereof in one adjustment corresponds to an off-normal position of the switch in a different adjustment.
12. In a registering apparatus containing a plurality of registering devices, a circuit path over which a plurality of series of impulses are received, means for directing successive series of impulses to separate registering devices and for directing one series of impulses so that it does not reach any registering device.
13. In combination, registering devices each arranged to register a series of impulses and a non-registering device, an impulse distributor, and means for operating said distributor between series of impulses so that a plurality of series of impulses are directed to a like plurality of said registering devices and one series of impulses is directed to said non-registering device.
14. In combination, registering devices each arranged to register a series of impulses, an impulse distributor arranged to distribute series of impulses to said devices successively, conductors extending from said distributor to said devices, and cross-connecting means in- terposed in said conductors between said distributor and said devices.
15. In a telephone system wherein impulse series corresponding to characters in telephone numbers are transmitted in succession incidental to the setting up of telephone connections, apparatus for registering a plurality of the characters in a telephone number and for absorbing another of the characters, and means for altering said apparatus so that a character of any one of a plurality of ranks may be the one absorbed.
16. In a telephone system wherein groups of impulse series are transmitted incidental to the setting up of telephone connections, means for absorbing or nullifying a series, and means for adjusting the absorbing means to absorb any desired one of a plurality of series.
17. In combination, means for transmitting a plurality of series of impulses, and means for absorbing or nullifying any desired one of said series.
18. In combination, means for receiving a plurality of impulse series, and means for absorbing or nullifying any desired series of received impulses.
19. A telephone system in which initial letters of names of exchanges are transmitted in the same manner as the numbers of wanted subscribers, characterized in that the receiving apparatus is provided with means for suppressing one or more of the letters transmitted thereto so that such letter or letters are rendered non-effective in controlling the setting up of a connection, the transmitted letters being received on a register which controls the transmission of impulses by an impulse sender according to a code having no numerical relationship to the impulses received.
20. A telephone system in which initial letters of names of exchanges are transmitted in the same manner as the numbers of wanted subscribers and in which receiving apparatus is provided common to a plurality of trunk lines, characterized in that the receiving apparatus is provided with means for suppressing one or more of the letters transmitted thereto so that such letter or letters are rendered non-effective in controlling the setting up of a connection, the transmitted letters being received on a register which controls the transmission of impulses by an impulse sender according to a code having no numerical relationship to the impulses received, said register being adapted to receive three transmitted letters and to record only two.
- In testimony whereof I hereunto affix my signature.
- RICHARD MERCER.
